 LLP(57) **CLAIM**

The ornamental design for a razor stand, as shown and described.

DESCRIPTION

FIG. 1 is a perspective view of the razor stand showing my new design

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings depict portions of the razor stand that form no part of the claim.
